INTERNAL-COMBUSTION ENGINE

Marcel Brigaudeau, Annecy, France

Application June 20, 1947, Serial No. 755,910
In France July 2, 1946

1 Claim. (Cl. 123—43)

1

My invention has for its object a novel type of internal combustion or explosion engine that is considerably simplified with reference to the engines now extant through the fact that it does away with the connecting rods, crankshafts and possibly with the valves, all said members being of a high cost price and of a comparatively low reliability and requiring constant upkeep and submitted to a rapid wear.

My improved engine is characterized by the fact that it includes an even number of groups of cylinders that are associated two by two and form with one another a suitable angle preferably of 90°, said cylinder groups substantially touching one another through their base circumference, said groups are constituted by cylindrical elements rotating inside a crank case holding them and are provided with a plurality of cylindrical recesses with parallel axes uniformly distributed round the axis of the group.

The corresponding cylinders of each of the two associated groups receive rigid pistons forming with one another an angle equal to that formed between said groups of cylinders and ensure their synchronous rotation by playing with reference thereto the part of connecting rods and cranks.

This synchronous rotation corresponds to a tacking or shuffling movement of the pistons in the cylinders inside which they define variable volume chambers that are used for ensuring the desired operating driving cycles which may be two-stroke according to the distribution system adopted.

The synchronous rotary movement of these cylinder groups round the corresponding axes as due to the driving stress is then made use of by inserting an output shaft along the axis of one of them while an auxiliary movement transmission member is possibly provided on the other group.

In the case of a two-stroke cycle, the distribution may be ensured through a system of ports suitably arranged, one of the two associated cylinder groups forming the power group while the other acts as a preliminary compressor and the connection between them is ensured through a stationary central tube or any like connecting means such as an outer tube, the crank case itself and the like.

It is apparent that I obtain thus an engine the principal advantages of which with reference to those used heretofore may be mentioned herein-after:

Omission in the mechanical system of the connection rods and crankshaft and possibly of the valves,

2

Substantial reduction in the ratio between weight and useful power,

Simplification in execution,

Increase in the coefficient of safety through the omission of brittle parts and a reduction in the number of pivots,

Better and easier balancing of the moving members, the reciprocating movements being entirely and perfectly compensated,

10 More regular driving couple by reason of the number of cylinders,

Reduction in bulk,

Reduction in cost price.

15 My invention will be properly understood by referring to accompanying diagrammatic drawings given solely by way of examples and illustrating an application of my invention to a two-stroke engine formed by a single system of a pair of cylinder groups associated with one another.

20 In said drawings:

Fig. 1 in an elevational cross-sectional view through line I—I of Fig. 2.

Fig. 2 is a plan view partly in horizontal sectional view of the same engine through line II—II of Fig. 1.

25 In the case illustrated the engine includes two groups I and I', the group I performing the preliminary compression while the group I' forms the power group.

30 Each group shows substantially:

A stationary external cylindrical crank case I—I' provided with cooling fins,

35 A cylinder block 2—2' adapted to rotate inside said casing and provided with one or more cylindrical bores 3 and 3' the number of which is four for each group in the case illustrated,

Rigid double pistons the elementary pistons being shown respectively at 7 and 7'.

The crankcase of the power group I' shows at 40 the location of the sparking plug, a single sparking plug being required for the whole system, each cylinder showing at the desired moment (position D) in front of said location an ignition port 13.

45 Furthermore, the crankcases I and I' are angularly shifted with reference to one another so as to form an angle of 90° in the case illustrated, said crankcases being in contact relationship through the adjacent parts of the base circumferences of the cylinders. Said crankcases are connected together through a tubular member 5.

The pistons of each double piston system 7—7' are obviously at right angles with reference to one another.

55 The two cylinder blocks 2 and 2' show a central blind hole, the blind holes of each cylinder block

communicating together through a stationary bent tube 6, passing inside the tubular member 5.

Ports 8-8' are provided in the crankcase 1-1' respectively for suction and exhaust. The distribution is ensured through ports 9 and 10 and 9'-10' provided in the cylinders, and 11-11' in the tube 6.

Assuming one of the cylindrical recesses executes a rotary movement round its axis, while the relative position of the axes of the two groups remains invariable, the consequence is that the other group will execute a synchronous rotation with reference to the first group. The double pistons are thus all the more deeply engaged inside their cylinders when they are nearer the point of contact between the cylinders of the two groups and the variable volumes thus defined between the head of the pistons and the cooperating covers of the cylinders pass for each revolution through a maximum and a minimum corresponding to the passage in the plane containing the axes of the two cylinder blocks.

Conversely, it will be immediately apparent that the cylinder blocks may rotate round their axis while remaining in contact and that any expanding force applied to a piston head at the moment at which the variable volume is a minimum will urge said piston away from the bottom of such cylinder. The piston will then behave after the manner of a connecting rod inside the driving cylinder and as an operative crank in the corresponding cylinder of the other cylinder block. The latter will thus be submitted to a stress tangential to the circumference described by the centre of the cylinder round the axis of the cylinder block. The consequent movement will therefore be a rotation of the cylinder block round its axis.

The movement of the piston will therefore be a tacking or reciprocating movement which is a consequence of the cooperation of their reciprocating and rotary movements.

Obviously, if through suitable timing means the cycle of operation of an internal combustion engine is applied to each variable volume chamber there is obtained a power system that replaces to advantage the poly-cylindrical engines now in use.

In the case of the two-stroke engine illustrated in the drawings, the cycle is performed as follows:

The suction is executed through the ports 8 and 9 into the cylinder of the preliminary compression group which is then at its lower dead point (position A). The compression of the mixture thus admitted is executed inside the same cylinder until the piston enters its outer dead point (position B). The uncovering of the ports 10 and 11 through registering thereof is then provided and the compressed mixture is in-

jected under pressure through the central stationary tube 6 and flows through ports 10' and 11' that are in register into the power cylinder that is then at its lower dead point (position C). This compressed mixture is then finally compressed until the upper dead point is reached as illustrated at D. Ignition is then produced and the expansion of the gases produces then the driving stroke with a return into the position C for which the exhaust is produced through the registering ports 9', 8'.

The angular setting and the size of the ports considered should obviously be suitably defined in the same manner as for any other engine.

The driving shaft 12 is axially located with reference to one of the cylinder blocks and is rigid therewith. In the case illustrated, said driving shaft is rigid with the preliminary compression cylinder block 1.

Lastly as obvious and as apparent from the preceding disclosure, my invention is by no means limited to the sole form of execution disclosed hereinabove in a diagrammatic manner and it covers on the contrary all the modifications of execution and all applications falling within the scope of the accompanying claim.

What I claim is:

An internal combustion engine including a crankcase provided with an even number of cooperating rotary circular surfaces forming with one another a predetermined constant angle and the axes of which intersect one another, two different groups each including cylinder elements and piston elements, the said groups being uniformly distributed round the axis of each of said rotary surfaces, one of the said groups acting as the compressor and the other as the motor, the cylinder and piston elements of each group being adapted to move slidingly with reference to one another, the piston elements of one group being rigid with the piston elements of the other associated group and being adapted to assume a movement of cylinder elements of two same groups round the two axes considered while remaining constantly in a plane parallel with the plane defined by said axes, and a stationary central knee-shaped injector tube connection between the compressor cylinder group and the explosion chamber of the motor cylinder group.
